UNITED STATES PATENT OFFICE.

KARL STEGMANN, OF BAUTZEN, GERMANY, ASSIGNOR TO JOHNE-WERK GRAFISCHE MASCHINEN-AKTIENGESELLSCHAFT, OF BAUTZEN, GERMANY.

CUTTING MACHINE FOR PAPER, CARDBOARD, AND THE LIKE.

Application filed May 28, 1925, Serial No. 33,416, and in Germany October 18, 1924.

This invention relates to a cutting machine for paper, cardboard and the like.

According to the invention the pressing beam is connected with springs, which are 5 permanently under compression, so that these springs press the pressing beam against the pile, while by a positive connection of the press lever system with the driving crank the lifting of the pressing beam is effected 10 in further compressing the springs. The positive connection is automatically disconnected when the pressing beam in descending encounters resistance.

In order to ensure the positive connection 15 the journal of the pressing lever engages a longitudinal slot of the connecting rod hingedly connected with the crank pin so that, as soon as the pressing beam encounters resistance when it descends, the connecting rod 20 can continue to move independently of the pressing beam.

Up to this moment the elastic pressure of the pressing beam exerts at the descent a driving action upon the crank pin.

25 An especially favorable form of construction consists in mounting one or several pressing springs between levers which are coupled so that they move in opposite directions, said levers pressing the beam on the 30 pile, the pressure and counter-pressure of the same springs acting the one on the one side of the pressing beam and the other on the other side of the same. Evidently any other equivalent means, for instance pneumatic pressure, might be substituted for the 35 spring pressure.

The spring pressure according to the actual position of the pressing beam acts in 40 this arrangement in full force upon each side of the pressing beam. As the sets of driving levers between pressing springs and pressing beam comprise, in this form of construction, on both sides of the pressing beam the same number of hinged connections the 45 wear and the play due to this wear will be equal so that, in opposition to the machines of known type, the same pressing pressure is always ensured for both sides of the machine.

50 The cutting period and the period for putting the springs under tension are preferably arranged so that they do not coincide and do not overlap one another and so that the machine is, during the cutting period, relieved of any pressing work. A specially

strong spring pressure can be obtained with the mechanism according to the invention, in a small space, if several spiral pressing springs are telescoped one within another.

In comparison with the spring pressings 60 on cutting machines commonly used the invention presents the advantage that with little driving power an especially strong pressing and consequently an especially accurate cutting by the machine can be obtained. 65

The power required for putting the springs under compression is, in this machine, practically zero if the machine works with full cutting height of material so that 70 the entire power is at disposal for the cutting. The work of the spring increases, therefore, only when the height of the pile decreases, e. g. at decreasing cutting height whereby a good equalization of power is 75 obtained. The machine possesses the further advantage that the spring pressure remains uniform during the entire cutting period and, as is necessary, increases in proportion to the height of the pile of paper. 80

This spring pressure which remains uniform is produced prior to the beginning of the cutting and remains the same during the entire cutting operation until the knife has again arrived above the pile. 85

When the pile is very high the driving crank acting upon the pressing lever will, for instance, act upon this pressing lever only for a short time in order to lift the pressing beam a few millimeters. During 90 the remainder of the rotation the crank pin and the connecting rod are absolutely relieved so that the whole driving power is available for driving the knife. A further 95 advantage of this machine is that the stroke of the knife is shorter owing to the fact that the knife need not move in advance.

An embodiment of the invention is shown, by way of example, in the only figure of the accompanying drawing, which shows somewhat diagrammatically a front elevation of the device. 100

The pull rods 2 and 3 are hingedly connected by means of bolts 4, 6 with the pressing beam 1 which is suspended in the usual manner. The pull rods 2, 3 are hingedly connected at the lower ends by means of bolts 5 and 7 with levers 8 and 9 pivotally mounted on axles 27 and 26. The levers 8 and 9 are rigidly connected with levers 10, 110

11 respectively. The levers 10, 11 are hingedly connected by means of bolts 14 and 15 with spring blocks between which spiral springs 12 and 13 are clamped, said springs being inserted the one in the other.

The levers 10 and 28 are connected the one with the other by a rod 22 so that all movements which the lever system 7, 11 executes in clockwise direction are transmitted in anticlockwise direction upon the levers 8, 10.

The springs 12 and 13 press the pressing beam 1 permanently down onto the paper pile 25. The lever 28, rigidly connected with the lever system 7, 11, carries at its end a stud 17 engaging with a longitudinal slot of the connecting rod 16 which is hingedly connected with the crank pin 18. When the crank pin 18 rotates from the left 20 dead point to the right dead point the stationary stud 17 slides at first in the slot of the connecting rod 16 until it arrives at the end of this slot. From this moment the connecting rod draws the stud 17 and consequently the pressing lever 28 along whereby the entire lever system 7, 11 and with the same (also the lever system 8, 10) is oscillated through the intermediary of the coupling rod 22. By this oscillating movement the 30 pressing beam 1 is lifted off the paper pile.

The paper pile is shown in the figure of the drawing at its maximum height. In this case the pressing beam is lifted only for a very short distance. The connecting rod 35 16 acts therefore upon the crank pin 17 for a very short time only. When the crank pin has passed beyond the right dead point position the stud 17 participates at first in the movement of the connecting rod 16 until the pressing beam 1 comes in contact with the paper pile 25. From this moment the stud 17 is stationary and the connecting rod 16 continues to move without exerting any power.

15 A crank pin 19 operates the knife through the intermediary of a pull rod 29. This crank pin 19 is displaced with regard to crank pin 18 in such a manner that the cutting begins only when the period of putting the springs under tension has finished and it is terminated before the pressing period begins.

I claim:—

1. A machine for cutting piles of paper,

cardboard, and the like comprising a pressing beam, a pair of levers, means for connecting one end of each lever to a corresponding end of the pressing beam, means for connecting said levers so that they move in unison in opposite directions, a resilient member interposed between the other ends of said levers, the pressure and counter pressure of said resilient member each acting on one end of said beam through the levers, and tending to press the beam against the pile of papers, and means for rotating said levers against the action of said resilient member to raise said pressing beam.

2. A machine for cutting piles of paper, cardboard, and the like in accordance with claim 1 in which the means for raising the pressing beam comprises a connecting rod having a lost motion connection with one of said levers, and a crank for reciprocating said connecting rod.

3. A machine for cutting piles of paper, cardboard, and the like in accordance with claim 1 in which the means for raising the pressing beam comprises a connecting rod having a pin and slot connection with one of said levers and a crank for reciprocating said connecting rod and a second crank rigid with the first having a second connecting rod pivoted thereto adapted to reciprocate a knife, the cutting period of the knife and the spring tensioning period being so timed that they do not overlap, whereby the machine during cutting is relieved of pressing work.

4. A paper cutting machine in accordance with claim 1 in which the resilient member comprises a plurality of telescoped springs.

5. A paper cutting machine comprising a pressing beam, a pair of levers, means for connecting one end of each lever to a corresponding end of the pressing beam, a resilient member interposed between the other ends of said levers, the pressure and counter pressure of said resilient member each acting on one side of said beam through the levers, and tending to press the beam against the paper, and means for rotating the levers to raise the pressing beam from the paper, said means influencing the levers only during the pressing beam raising stroke.

The foregoing specification signed at Bautzen this 25 day of April, 1925.

KARL STEGMANN.
